UNITED STATES PATENT OFFICE

CHARLES F. SMITH, OF BROOKLYN, NEW YORK, ASSIGNOR, BY MESNE ASSIGNMENTS, TO LILY-TULIP CUP CORPORATION, OF NEW YORK, N. Y., A CORPORATION OF DELAWARE

PAPER CUP MACHINE

Application filed April 6, 1927. Serial No. 181,475.

This invention relates to paper cup machines and has for its object to provide a machine preferably organized in three grand divisions, for continuously making two piece paper cups, the finished cup having a body wrapped around a flanged bottom, the bottom carrying end of the body being folded inwardly over the flange, the brim of the cup also being folded inwardly.

Among the objects of my invention is to concurrently operate at each of a complete cycle of stations upon the cup forming material and continuously discharge the completely formed cups, and to provide a machine of this character which is highly efficient and speedy in operation and accurate in product. To these ends and others which will appear later herein, my improvements comprise features illustrated in their preferred embodiment in the drawings accompanying this specification, wherein:

Figure 1 is a plan view of right hand end portion of the machine.

Fig. 2 is a similar plan of the middle portion of the machine.

Fig. 3 is a similar plan of the left hand end portion of the machine.

These three plan views slightly overlap so as to properly relate to one another.

Fig. 4 is a front elevation, with part of the base casing removed, of what is shown in plan in Fig. 1.

Fig. 5 is a sectional elevation on line 5, 5, Fig. 2 of the midportion of the machine. Fig. 5a is a fragmentary vertical section on line 5—5 of Fig. 2 showing the upper right hand portion of Fig. 5.

Fig. 6 is a similar sectional elevation corresponding with the plan of Fig. 3 and the section is taken on line 6, 6 of said Fig. 3. Fig. 6a is a fragmentary perspective view of the cup ejector of Fig. 6.

Fig. 7 is an end elevation looking in the direction of arrow 7, Fig. 1.

Fig. 8 is a detail sectional elevation on line 8, 8 of Fig. 1.

Fig. 9 is a similar detail sectional elevation on line 9, 9 of Fig. 1.

Fig. 10 is a sectional elevation on line 10, 10 of Fig. 1.

Fig. 11 is a similar sectional elevation on line 11, 11 of Fig. 1.

Fig. 12 is a detail sectional elevation on line 12, 12 of Fig. 4.

Fig. 13 is a sectional elevation on line 13, 13 of Fig. 1.

Fig. 14 is a face view of the cup-bottom die looking in the direction of arrow 14 in Fig. 13.

Fig. 15 is an elevation of a detail looking in the direction of arrow 15, Fig. 7.

Fig. 16 is a fragmentary elevation looking in the direction of arrow 16 in Fig. 2.

Fig. 17 is a fragmentary elevation, partly in section, looking in the direction of arrow 17 in Fig. 2. Fig. 17a is a sectional view of the bottom flange turning die of Fig. 17. Fig. 17b is a view similar to that of Fig. 17a but with the parts in different positions.

Fig. 18 is a similar fragmentary elevation looking in the direction of arrow 18 of Fig. 2.

Fig. 19 is a detail elevation looking in the direction of arrow 19 in Fig. 3.

Figs. 20 to 26 inclusive, illustrate the several steps in the formation of a cup by my improved machine.

The scale of Figs. 1 to 7 inclusive, 12, and 16 to 19 inclusive is the same, with the exception of Fig. 5a, which is one and one half times larger; Fig. 6a, which is two and one half times larger and Figs. 17a and b which are two times larger. The scale of Figs. 8 to 11 and 13 to 15 inclusive and Fig. 20 is twice that of Fig. 6. The scale of Figs. 21 to 26 inclusive is eight times that of Fig. 1.

The present machine is designed to perform the several operations in the production of a two-piece paper cup or container, the body of which is formed from a blank 2, Fig. 20, comprising a sector of an annular ring. This body blank is provided with score lines 21, 22, near its opposite long curved edges respectively for purposes presently to be explained. The cup bottom 30 is formed from a circular disc punched from a continuous strip of paper or the like, and said disc has its edge erected into a flange 20, Fig. 22.

This bottom is held against the smaller end of a conical mandrel and about that man-

drel and cup-bottom the body blank 2 is wrapped with the flange edge of said bottom in coincidence with score line 22, Fig. 22. Body blank 2 is of sufficient length to twice enwrap said mandrel with its outer end 3 overlapping the inner end 4 of said body blank, Fig. 21. Paste or some other suitable adhesive is applied to a portion of the inner face of body 2 just before said body is wrapped. Paste is then applied to the inner face of the bottom 23 of the cup body and that lower edge is next rolled inwardly over bottom flange 20, Fig. 23, and finally the pasted inner face of said edge 23 is set snugly against the inner face of said flange 20, Fig. 24. The inner face of edge 24 of the mouth of the cup body then has paste applied thereto and said edge is rolled inwardly on score line 21, Fig. 20, and finally folded snugly with its pasted inner face against the inside of the cup mouth, Fig. 26, thereby completing the formation of the cup.

The present machine is an organization of mechanisms directed to the production of the two-piece cup, the steps in the formation of which have just been rehearsed. The several devices direct to this end are preferably mounted upon a unitary base 28. Just above said base and supported thereby in suitable bearings, 29, 31, 32 and 23, Figs. 4, 5 and 6, is main shaft 35. This shaft may be driven from any convenient source of power, but I preferably employ electric motor 80, which through gears, 81, 82 and worm 83 drives worm gear 84 fixed to said shaft 35, Figs. 2 and 5.

While my improved machine is a unitary organization, for purposes of description it readily falls into three grand divisions.

40 The first grand division, shown assembled in Figs. 1 and 4 is directed principally to feeding the body blanks from the bottom of a stack of blanks 25, Fig. 7, creasing and pasting those blanks and delivering them to the mandrel 26. It also includes the punching of the bottom, the forming of the flange thereon and the delivery of that bottom against the end of mandrel 26, after which the body blank is wrapped about said mandrel and bottom.

50 The second grand division, shown assembled in Figs. 2 and 5, comprises principally, a rotary carrier 27, fixed to vertical tubular shaft 207, with which it rotates in clockwise direction, Fig. 2. From said carrier protrude horizontally, a plurality of mandrels as 26. At several stations about the periphery of said carrier, operations directed to the production of the cup are performed.

60 The third grand division, shown assembled in Figs. 3 and 6 comprises another rotary carrier 37 fixed to vertical tubular shaft 316, with which it rotates in anti-clockwise direction, Fig. 3. From said carrier protrude horizontally a plurality of cup receptacles or

dies, as 39. At several stations about the periphery of said carrier, operations directed to the completion of the cup and to the rejection of any cup which may have failed to receive a bottom, are performed and the completed cups discharged from the machine.

First grand division

Body-blank feeding mechanism.—In the upper right hand portion of Fig. 1 this mechanism is supported on casing 34. See also Figs. 7, 8 and 9. This mechanism is slightly inclined to the horizontal, see Fig. 7, the angle of inclination being the same as that of the cup body to the cup axis, so that the blanks are delivered to the body wrapping mechanism tangential to the mandrel. A stack 25, Fig. 7, of body blanks 2, Fig. 20, are supported on table 40 between guides 41, 41 and the right hand ends of those blanks, Figs. 1 and 4 project beyond said table, over and for engagement with suction feed roll 42, shown in detail in Fig. 8. Said suction roll and lower feed roll 43, together with secondary feed rolls 44, 45 have bearings in housing 46 and are driven at equal surface speed by the following means. Fixed to main shaft 35 is miter gear 47 meshing with and driving miter gear 48 fixed to horizontal shaft 49, Fig. 12. To the outboard end of said shaft 49 is fixed miter gear 50 meshing with and driving miter gear 51 fixed to short vertical shaft 52, having bearings in brackets extending outwardly from a vertical wall of casing 34. Arm 53 extending to the left, Fig. 7, from housing 46, has a bearing for upright shaft 54, Fig. 9, and to which shaft is fixed bevel gear 55 meshing with and driving smaller bevel gear 56 fixed to one end of shaft 57 of roll 45. To the other end of said shaft 57 is fixed gear 58 meshing with and driving equal gear 59 fixed to shaft 60 of roll 44. The upper end of shaft 54 and the lower end of shaft 57 are operatively connected by coupler 61 having universal joints at either end thereof. Power is communicated from gear 58 to gear 62, fixed to suction roll shaft 63, through two intermediate gears 64, 65, Fig. 4, and gear 62 meshes with and drives gear 66 fixed to shaft 67 of roll 43. Roll 43 is urged upwardly to coaction with suction roll 42 by the usual spring impelled bearing boxes, Fig. 8, and roll 44 is urged downwardly to coaction with roll 45 by similar spring impelled bearing boxes.

105 Suction roll shaft 63 has lengthwise channel 68 therein and port 69 thereof communicates with suction chamber 70 of said roll 42. The air is exhausted from chamber 70, 125 at suitable times, through port 71 in shaft 63 when that port rotates into coincidence with port 72 of sleeve 73. Air is exhausted from the chamber between sleeve 73 and the outer casing through pipe 74 connecting with said 130

110 115 120 125 130

casing, by some convenient known means, not shown.

Base 75 of housing 46 may be shifted transversely on casing 34, Fig. 1, bolts 76, 76 being slideable in slot 77, for adjusting the two pairs of body blank feeding rolls toward or from the conical feed rolls shown in section in Fig. 10. From rolls 44, 45 the body blank is delivered to two pairs of successively acting conical rolls and thence to the pasting device and to the forming mandrel.

But prior to such delivery of the body blank, the cup bottom 30, Fig. 22, is punched from a web of paper 78, Fig. 15, has a flange 15 formed thereon and said bottom is delivered against the right hand end of mandrel 26, Figs. 1 and 4. Said web of paper is fed intermittently downwardly in front of cutting die 79, Fig. 13, between feed rolls 85, 20, 86, Fig. 7. Said web feed mechanism is canted as shown in said Fig. 7, for purposes of convenience, to avoid conflict with other mechanism. Said rolls are geared together as usual and smaller roll 85 is mounted in eccentric bearings so that by swinging lever 87 to the left, Fig. 15, said rolls may be slightly separated for threading the web therebetween. Also boxes as 88 for roll 85 are urged toward roll 86 by the usual springs as 89. 25 Roll 86 is rotated intermittently by the following means: Roll shaft 90 has miter gear 91 fixed to one end thereof and miter gear 92 fixed to the upper end of shaft 93. To the lower end of shaft 93 is fixed miter gear 94 meshing with miter gear 95 fixed to one end of horizontal shaft 96. On the other end of shaft 96, Figs. 1 and 4, disc 97 is mounted for free oscillation and carries spring urged pawl 98 for engagement with the teeth of ratchet 40 99 fixed to shaft 96 between disc 97 and shaft bearing 100. To that end of main shaft 35, adjacent box 29 is fixed disc 101 in which is mounted crank pin 102 adjustable toward and from the center of said disc by means of 45 screw 103. On said crank pin 102 is pivoted one end of link 104 and the other end thereof is pivoted near the periphery of disc 97 of shaft 96. Upon the rotation of disc 101 upper disc 97 is oscillated and shaft 96 intermittently rotated, the amount of such oscillation being governed by the adjusted distance of 50 crank pin 102 from the axis of shaft 35.

Directing attention now to Figs. 1 and 13, after the web of paper 78 is delivered intermittently in front of die 79, by the means just described, punch 105 advances to the left and spring supported presser foot 106 clamps the paper web against die 79, immediately followed by the entrance of said punch into the die, whereby a disc of paper is punched from the web. Directly following, forming punch 107 advances to the left and pushes the paper disc into drawing die 108 and through that die into bottom carrier 109.

55 For accurately centering dies 79 and 108

relatively to punches 105 and 107, said dies may be slightly shifted by means of dogs as 110 having inclined heels as 111 and which dogs are adjustably secured by bolts as 112, Fig. 14.

For imparting sliding movement to punches 105 and 107 the following means are provided: Punch 105 is tubular, punch 107 sliding within it. Said punch 105 is mounted within the left hand end of slide 113, of 70 rectangular cross section, and is secured in place therein by cap 114 and which cap carries the springs for presser foot 106, Fig. 1. Said slide 113 has in its lower portion transverse slot 115, in which slides block 116 in 75 which is pivoted crank pin 117 of disc 118 fixed to the upper end of vertical shaft 119. To the lower end of shaft 119 is fixed gear 120 meshing with and driven by equal gear 121 fixed to vertical shaft 122. Said shaft 122 has fixed to its upper end disc 123 having crank pin 124 thereof pivoted in block 125 adapted to slide in transverse slot 126 of slide 127, of rectangular cross section. Sleeve 128 passes lengthwise through slide 127 and is 80 adjustable lengthwise therein. Forming punch 107 is axially secured within sleeve 128. Shaft 122 is rotated to the right, Figs. 12 and 13, from main shaft 35, through miter gear 47, fixed to said main shaft and which 85 gear meshes with and drives miter gear 129 fixed to the left hand end of horizontal shaft 130. Miter gear 131, also fixed to shaft 130, drives miter gear 132 fixed to the lower end of shaft 133 connected by coupling 134 to 90 shaft 122.

Bottom carrier 109 is adjustably supported at the outer end of arm 135, which turns on stud 136, and opposite said arm 135 is Geneva arm 137 which is actuated by pin 138 of oscillating arm 139, turning on shaft 140. Fixed to arm 139 is gear 141 driven by segment gear 142 pivoted at 143. Said segment gear 142 has pin 144 engaged and actuated by cam 145 fixed to vertical shaft 146, 110 see Figs. 4, 7 and 13. Shaft 146 has miter gear 147 fixed to its lower end, driven by miter gear 148 fixed to main shaft 35. By this mechanism bottom carrier 109 is swung from the position of Fig. 7 to deliver the cup 115 bottom in front of rotatably mounted head 149 of mandrel 26, Figs. 1, 4 and 5.

Plunger 150 then advances to the left, Fig. 4, and delivers the cup bottom out of carrier 109 against said mandrel head 149 and follows that head back into its seat in the end of the mandrel. Bottom carrier 109 having thus performed its function, is free to return to its position before die 108, which it presently does, opening 157 therein permitting its withdrawal over the shank of plunger 150 without interference.

Said plunger 150 is mounted on the left hand end of slide 151 and the right hand end of said slide is connected by link 152 with the 125 130

upper end of lever 153 pivoted at 154. The lower end of said lever has roll 155 in engagement with the groove of cam 156 fixed to main shaft 35.

- 5 Reverting now to Figs. 1, 10 and 11, during the forming and delivering of the cup bottom, body blank 2 is advanced by the conical rolls of Fig. 10 to the pasting device and directly after the delivery of the cup bottom 10 against the mandrel, is wrapped about said mandrel. Between rolls 44, 45 and the conical rolls, table 158 is provided to support and guide the body blank. The two pairs of conical rolls are mounted on frame 159, pivoted 15 for adjustment toward and from rolls 44, 45, on sleeve 160 fixed in the top wall of casing 34, Fig. 11.

Of the first pair of conical rolls, lower roll 161, Fig. 1, is fixed to shaft 162 and has miter gear 163 thereof driven by miter gear 164 fixed to the upper end of vertical shaft 165 in frame 159. To the lower end of said shaft 165 is fixed spur gear 166, driven by larger gear 167, coaxial with frame 159, Fig. 11. 25 Upper conical roll 168 is geared to lower roll 161 and the second pair of conical rolls 169, 170 are similarly geared together while power is transmitted from the gear of lower roll 161 to the gear of lower roll 169 by intermediate 30 gear 171. Conical rolls 169, 170 are provided with means, as ribs 172, 173 to roll 169, for forming in body blank 2, Fig. 20, creases 21, 22, on which creases said blank is later folded. A transfer table, not shown, similar to 158, 35 is preferably employed between conical rolls 169, 170 and mandrel 26 to guide the body blank.

Paste is applied to the body blank as it is passed from rolls 169, 170 to mandrel 26 by 40 the following means: Paste receptacle 174, Figs. 1, 4 and 7, has conical roll 175 constantly engaging the paste in said receptacle. Said roll has a slight up and down movement, being mounted in oscillating arm 176 pivoted on 45 shaft 177 and said arm carries roll scraper 178. The shaft of paste roll 175 has gear 179 fixed thereto, meshing with intermediate gear 180 on shaft 177 and gear 181 fixed to shaft 182 drives gear 180. Also to shaft 182 is 50 fixed miter gear 183 driven by miter gear 184 fixed to the upper end of vertical shaft 185. To the lower end of said shaft 185 is fixed miter gear 186 driven by miter gear 187 fixed to the left hand end of horizontal shaft 188, 55 Fig. 4. To the other end of said shaft is fixed pinion 189 driven by gear 190 fixed to main shaft 35. For moving paste roll 175 up and down arm 176 is pivoted to the upper end of adjustable pitman 191 and the lower end of 60 said pitman is pivoted at 192 to one end of lever 193. The other end of said lever carries roll 194 in engagement with cam 195 fixed to main shaft 35.

For rolling the body blank against the 65 mandrel, upper conical roll 196 is provided.

This roll is fixed to the left hand end of shaft 197, Fig. 4, and said shaft points upwardly toward said roll and turns in frame 198, pivoted about shaft 199, Fig. 11. Said frame is urged downwardly by a spring 70 within spring box 200, Fig. 4. Said shaft 197 is driven from vertical shaft 146 as follows: Large gear 167 fixed to shaft 146 drives pinion 201 fixed to the lower end of shaft 202 and miter gear 203 fixed to the upper end of shaft 202 drives miter gear 204 fixed to shaft 199. Miter gear 205 also fixed to shaft 199 drives miter gear 206 fixed to the inboard end of shaft 197.

75

75

80

Second grand division

In this portion of the machine, shown in Figs. 2 and 5, the wrapping of the body blank about mandrel 26 is completed, station A, in coaction with mechanism already described in the first grand division. Also the inside of bottom flange 23 of the cup is gummed, station B, and that flange turned inwardly, station C, and then pressed against flange 20 of the cup bottom, station D, Figs. 23 and 24.

85

Central sleeve 207 of rotary carrier 27 has its bearing in long hub 208 of casing 34A and vertical shaft 36 projects upwardly through and turns freely in said hub. To the lower end of said shaft 36 are fixed spur gear 209 and miter gear 210. Meshing with and driving miter gear 210 is miter gear 211 fixed to main shaft 35. Driven by spur gear 209 is equal gear 212 which carries crank pin for engagement with Geneva gear 214 for imparting intermittent rotary movement to carrier 27.

90

Said carrier is provided with a plurality of horizontal, radially arranged shafts as 105 shaft 215, to the outer end of which is fixed mandrel 26. These shafts have bearings in brackets as 216 fixed to carrier 27 and are rotated from vertical shaft 36 through large bevel gears 217 fixed thereto meshing with 110 and driving small bevel gears, as 218, fixed to the inboard end of shaft 215. Said shaft 215 is tubular, rod 219 being slidably mounted therein. The outboard end of rod 219 has mandrel head 149 fixed thereto and the inboard end engages between a pair of collars the yoked upper end of arm 220, whose lower end is fixed to slide 221 having bearings in bracket 216. The cutboard end of said slide carries roll 222 for engagement with the upper end of lever 223 pivoted in bracket 224 on base 28 of the machine. Said roll 222 also engages fixed cam 225 of casing 34A. At predetermined times rod 219 is slid inwardly 115 to retract mandrel head 149, by means of lever 223, which is actuated by cam 226 fixed to main shaft 35. To this end lever 227 pivoted at 228 has roll 229 carried by its lower end in engagement with the groove of cam 226.

110

115

120

125

130

For exhausting the air from ports 230 of mandrel 26, Fig. 5a, to pick up and retain the body blank against said mandrel, mandrel chamber 231 behind said ports is provided, and through a plurality of channels 232 in shaft 215 is connected with exhaust pipe 233 which in turn is threaded into central valve 234. As carrier 27 comes to a position of rest in its intermittent rotation, the 10 ports of valve 234 come into coincidence with corresponding ports in fixed plug 235. This plug is connected with some known source of exhaust not shown. In some cases the port in plug 235 may be a continuous annular 15 groove, thereby subjecting air ports 230 of mandrel 26 to continuous suction. The upper ports of carrier 27 are provided with hood 236, in the central upper portion of which valve 234 is formed.

20 The gearing which rotates mandrel 26 is timed to give that mandrel about two complete rotations while it dwells at station A to receive and roll up the body blank.

25 After said body blank is rolled about mandrel 26, carrier 27 rotates in clockwise direction, Fig. 2, to present the partially formed cup, comprising bottom 30 within the rolled up body blank, to the next station, B, where gum is applied to the inner face of rim 23, 30 Fig. 22, of the lower end of the cup body. This gumming mechanism is best shown in Fig. 16, wherein gum applying roll 237 is rotatably mounted above large gum roll 238, constantly rotating in gum dish 239. Said 35 roll 238 may be provided with the usual scrapers not shown. Small roll 237 is fixed to one end of a shaft to the other end of which is fixed pinion 240, driven by gear 241 fixed to one end of shaft 242 to the other end 40 of which gum roll 238 is fixed. Also fixed to shaft 242 is bevel gear 243 driven by larger bevel gear 244 fixed to the upper end of vertical tubular shaft 245. To the lower end of said tubular shaft 245 is fixed miter gear 246 45 which is driven by miter gear 247 fixed to the left hand end of horizontal shaft 248. To the right hand end of said horizontal shaft is fixed miter gear 249 driven by miter gear 250 fixed to main shaft 35.

50 When in operative position, gum roll 237 lies in the path of the partly formed cup on mandrel 26 as that mandrel travels in its orbital path about shaft 36, Fig. 2. Therefore means are provided to swing that roll and its immediate connecting mechanism out of said path during the movement of said mandrel from station to station. To this end, frame 251, in which the gum roll shafts have their bearings, is fixed to the upper end of shaft 252 which has its bearing within tubular shaft 245. To the lower end of shaft 252 is fixed arm 253 connected at its outer end by link 254 with arm 255 fixed to the lower end of oscillating vertical shaft 256. Said shaft 256 has bearings in the frame which supports

the gumming mechanism and has fixed thereto arm 257 which carries at its outer end a roll for engagement with cam 258 fixed to tubular shaft 245 about midway between miter gears 244 and 246. Thus, when the cam 70 roll is drawn toward shaft 245 by cam 258, the gum roll head 251 is rotated a slight amount in clockwise direction, Fig. 2, and roll 237 is swung out of the path of the cup on mandrel 26, large roll 238 being free to 75 swing in the same direction into the enlarged portion of gum dish 239. Then, after mandrel 26 has reached a position of rest, gum roll 237 is swung back into coacting relation with the cup thereon.

80 The mechanism at station C, Figs. 2, 17, 17a and 17b, is provided for turning inwardly the bottom flange 23 of the cup. A compound die, comprising an outer ring 259 within holder 260, and an inner plug 261 act successively on said flange. Said ring has an inwardly beveled front edge to encircle the cup bottom flange, and which edge as it advances onto said flange bends it inwardly. Serrated plug 261 is advanced with ring 259 and folds 90 said flange 23 outwardly toward bottom flange 20, Fig. 24. Holder 260 is threaded onto head 262 and members 259, 260 and 262 turn freely as one element on headed shaft 268. To limit the forward movement of ring 95 259, shouldered ring 265 is adjustably threaded into bushing 266 bolted to frame 264. When ring 259 has been advanced its full stroke, ball race ring 267 abuts against the inner face of the flange of ring 265 and 100 serrated plug 261 continues to advance, Fig. 17b, compressing springs 263 and the ball bearing permits free rotation of ring 259 with the cup. Shaft 268 is slidable axially in tubular shaft 270 and is constrained to rotate 105 therewith by key 269.

110 For rotating shaft 268 in the same direction and at the same speed as the cup, miter gear 271 is fixed to tubular shaft 270 and is driven by miter gear 272 fixed to the upper end of a vertical shaft to the lower end of which is fixed bevel gear 273 driven by larger bevel gear 274 fixed to the right hand end of horizontal shaft 275. To the left hand end of said shaft 275 is fixed bevel gear 276 115 driven by larger bevel gear 277 fixed to main shaft 35. For oscillating shaft 268 axially collars 278 engage therebetween opposite pins projecting from the upper end of lever 279 pivoted at 280. The lower end of said lever 120 is pivoted to yoke arm 281, the yoke portion of which straddles shaft 282, to which is fixed cam 283, the cam slot in which engages a roll carried by yoke arm 281. Said cam is rotated from shaft 275, through bevel gear 284 125 fixed to said shaft, driving larger bevel gear 285 fixed to cam shaft 282.

130 The next and final step in bottoming the cup is performed at station D, Figs. 2 and 18 where the partly inturned bottom flange

with gum therein is laid snugly against the cup bottom flange, Fig. 24. For this operation bevel roll 286, freely turning on the end of arm 287 is provided. Said arm is 5 fixed to cross shaft 288, so as to swing roll 286 out of the path of the cup and then into the cup bottom when the cup bearing mandrel has reached a position of rest at station D. Below the edge of the cup bottom, 10 fixed to shaft 289 transverse to shaft 288, is large roll 290 for supporting the cup bottom edge while the inner portion thereof is acted upon by bevel roll 286. Said roll is driven at the same surface speed as that of 15 the periphery of the cup with which it engages. Bevel gear 291 is fixed to shaft 289 and is driven by larger bevel gear 292 fixed to the upper end of vertical shaft 293. To the lower end of said shaft is fixed miter 20 gear 294 driven by miter gear 295 fixed to shaft 282. For oscillating shaft 288 and thereby swinging roll 286 into and out of engaging relation with the cup, said shaft has arm 296 fixed thereto and the outer end 25 of said arm is connected by adjustable link 297 with the outer end of lever 298, pivoted at 299. Between pivot 299 and the outer end of arm 298 a roll engages a cam slot in cam 300 fixed to vertical shaft 293.

30

Third grand division

At the next station, E, the bottomed cup is transferred to the third grand division and is received into one of a plurality of 35 dies or cup holders as 39, Figs. 3, 6 and 6a. To this end the cup is ejected from mandrel 26 by means of mandrel head 149 the operation of which has been previously described in connection with the withdrawal of that 40 plunger when the cup bottom is received by said plunger. Now the plunger is moved outwardly by the engagement of roll 222 of slide 221, with the upper end of lever 301 pivoted in bracket 302 on base 28 of the machine, left hand of Fig. 5. Said lever 301 is actuated from cam 303 fixed to shaft 35, Fig. 6, by means of link 304 pivotally connected to said lever at 305 and similarly pivoted to cam lever 306 at 307. 45 Said lever 306 is pivoted at 308 and its lower end carries a roll for engagement with the cam slot of cam 303. To permit roll 222 to emerge from the circular portion of 50 cam slot 225, an opening is provided between horns 309, Fig. 2. The detail construction of cup holder 39, is best shown at the left of Fig. 6 and in Fig. 6a. Said holder is carried within head 310, fixed to the out- 55 board end of tubular shaft 311 and to the inboard end of said shaft bevel gear 312 is fixed. Said holder 39 and gear 312 are constantly rotated by large bevel gear 313, 60 fixed to the upper end of vertical central shaft 38, to the lower end of which is fixed 65

miter gear 314 driven by miter gear 315 fixed to main shaft 35.

Carrier 37, which supports the several cup holders as 39, has downwardly reaching tubular shaft 316 having its bearing in sleeve 70 317 of the machine frame. Said carrier is intermittently rotated by a Geneva mechanism similar to the mechanism which intermittently rotates carrier 27, Fig. 5. Gear 318 is fixed to shaft 38 and drives gear 319, 75 Fig. 3, to which is fixed crank pin 320 for engagement with Geneva gear 321 of carrier 37.

At station F, Fig. 3, the inside of the mouth 80 24 of the cup receives a coating of gum, by means of a gumming mechanism substantially like the gumming mechanism shown in Figs. 2 and 18, in connection with the gumming of the bottom flange of the cup. This gumming device of station F is driven from 85 shaft 322 connected by miter gears 323, 324 with main shaft 35, Fig. 6, and is swung into and out of engaging relation with the cup flange by cam means similar to that of 90 said Figs. 2 and 18.

At station G the mouth flange 24 of the cup is turned inwardly against the inside of the cup by means of a device substantially like that shown in Figs. 17 and 17a, for turning in the bottom flange 23. Compound die 325 carried by shaft 326 is rotated through miter gears 327, 328, the latter of which is fixed to a vertical shaft driven by gearing connected with bevel gear 329 on main shaft 35, Fig. 6. Said die 325 is reciprocated into and out of 100 engaging relation with the cup mouth by means of lever 330, yoke arm 331 and cam 332 fixed to shaft 333, driven from main shaft 35, by gearing similar to that of Fig. 17.

At station H, Fig. 3, the mouth flange 24 of the cup is rolled down against the inside of the mouth of the cup by a mechanism substantially like that of Fig. 18 for rolling down the bottom flange of the cup. Therein bevel roll 334 is swung into and out of the 105 cup mouth, but no under supporting roll, like roll 290, Fig. 18, is required as the pressure of roll 334 is supported by holder 39.

At station I, Fig. 3, the cup, if perfect and complete, is discharged from the machine, Figs. 6 and 6a. To this end a duplex plunger is mounted within tubular shaft 311. One member of said plunger includes small opposite head segments 335, Fig. 6a, fixed to the outboard end of tubular shaft 336. The inner end of said shaft has collars 337 between which is engaged the upper forked end of arm 338 fixed to the inner end of tubular slide 339. To the outer end of said slide is fixed roll 340 for engagement with the upper end 110 of lever 341. Said lever is oscillated to the left, Fig. 6 at predetermined times by cam 303 to which it is operatively connected by link 304 and lever 306 already described in 115 connection with other mechanism. Refer- 120

130

ring particularly to Fig. 3 it will be seen that stem 350 of roll 340 is offset to one side of transverse center line 6-6 and that stem 351 of roll 352, Fig. 19 is offset to the other side of said center line. The head of lever 341 oscillates outwardly between horns 353, the opening between which permits roll 340 to emerge from circular slot 354 which normally constrains said roll to a circular path. It will be observed that the diameter of head segments 335 is less than the inside diameter 23 of the cup bottom, so that said segments in their movement of ejection, will directly engage bottom 30, Fig. 24, thereby pushing the finished cup out of holder 39 and discharging it from the machine.

But, if the cup, by any mischance has failed to receive a bottom, segments 335 will move outward idly within the cup body and fail to discharge that bottomless body. Therefore none but complete bottomed cups will be discharged at station I.

At station J, Figs. 6 and 19, means are provided for clearing any bottomless cups which may pass station I. To this end head segments 342, Fig. 6a, set quartering from segments 335, are fixed to the outboard end of shaft 343 which is mounted for reciprocation within tubular shaft 336. The inner end of shaft 343 has collars 344 between which is engaged the upper yoked end of arm 345 fixed to the inner end of slide 346 within tubular slide 339. To the outboard end of slide 346 is fixed roll 352 and at station J the upper end of lever 347 engages both rolls 340, 352 and moves them outwardly between horns 349, thereby advancing all four segments 335, 342 whereby any bottomless body is ejected by segments 342, Fig. 19. Said lever 347 is pivoted at 348 on base 28 and is connected by link 355 with bellcrank lever 356 of shaft 357 the horizontal arm 358 of which carries a roll in engagement with cam 359 fixed to main shaft 35.

This completes the operation of the machine and that cup holder 39 at station J then continues its intermittent anticlockwise movement, Fig. 3, to station E where it receives another cup to be operated upon.

50 I claim:

1. In a paper cup machine the combination of cup bottom forming means including a compound die having a blank cutting member and an edge forming member, a pair of concentric punches for coaction with said compound die, means for feeding intermittently a web of paper across the face of said die and for timing its movement with said punches, a presser foot carried by the outer punch of said pair of punches, means for advancing said presser foot to clamp said web against said die and to cause said outer punch to coact with the blank cutting member of said die and means for advancing the inner punch of said pair of punches for coaction

with the edge forming member of said die, said presser foot, outer punch and inner punch acting successively.

2. In a paper cup machine the combination of a rotary carrier, a plurality of mandrels projecting radially from the axis of rotation of said carrier, a plurality of operating stations about the path of said mandrels, means for rotating intermittently said carrier for presenting said mandrels successively to successive operating stations, means for rotating said mandrels, a seat in the projecting end of each mandrel, a mandrel head in each seat, means for moving said head from and into its seat and means at one station for delivering a cup bottom against the projected mandrel head, said mandrel head moving means being timed to withdraw said head coincidentally with the delivery of a cup bottom thereagainst.

3. In a paper cup machine the combination of a rotary carrier, a plurality of mandrels projecting radially from the axis of rotation of said carrier, a plurality of operating stations about the path of said mandrels, means for rotating intermittently said carrier for presenting said mandrels successively to successive operating stations, means for rotating said mandrels, means at one station for delivering a cup bottom against the projecting end of a mandrel at said station, means for delivering a body blank about said mandrel, blank pasting means below said mandrel including a roll for applying paste to a blank on said mandrel and means for timing the several instrumentalities with each other.

4. In a paper cup machine the combination of a rotary carrier, a plurality of mandrels projecting radially from the axis of rotation of said carrier, a plurality of operating stations about the path of said mandrels, means for rotating intermittently said carrier for presenting said mandrels successively to successive operating stations, means for rotating said mandrels, means at one station for applying gum to the inner face of a cup body end projecting from a mandrel comprising a rotating gum applying roll, means for swinging said roll into and out of engagement with the cup body and means for supplying said roll with gum.

5. In a paper cup machine the combination of a rotary carrier, a plurality of mandrels projecting radially from the axis of rotation of said carrier, a plurality of operating stations about the path of said mandrels, means for rotating said mandrels, means at one station for turning inwardly the bottom flange of a cup body on a mandrel including a compound die capable of freely rotating with the cup body while in engagement therewith and having an outer ring with an inwardly beveled front edge for encircling and bending said flange inwardly, a plug within said

ring for folding said cup flange outwardly, means for moving said die onto said cup flange and means for timing the movement of said die with the intermittent rotation of said carrier.

6. In a paper cup machine the combination of a rotary carrier, a plurality of mandrels projecting radially from the axis of rotation of said carrier, a plurality of operating stations about the path of said mandrels, means for rotating said mandrels, means at one station for turning inwardly the bottom flange of a cup body on a mandrel including a rotating compound die having an outer ring with an inwardly beveled front edge for encircling and bending said flange inwardly, a plug within said ring for folding said cup flange outwardly, means for moving said die onto said cup flange, means for yieldingly limiting the movement of said outer ring while permitting the relative advancement of said plug and means for timing the movement of said die with the intermittent rotation of said carrier.
7. In a paper cup machine the combination of a rotary carrier, a plurality of mandrels projecting radially from the axis of rotation of said carrier, a plurality of operating stations about the path of said mandrels, means for rotating intermittently said carrier for presenting said mandrels successively to successive operating stations, means for rotating said mandrels, means at one station for folding inwardly a flange at the edge of a cup, means for rolling down the infolded cup flange including a roll mounted for free rotation, means for swinging said roll into and out of the cup, a rotating roll in cooperative relation with said cup flange roll for supporting the cup edge during the operation of rolling down said infolded flange and means for timing the several instrumentalities with each other.

8. In a paper cup machine the combination of a rotary carrier, a plurality of mandrels projecting radially from the axis of rotation of said carrier, a plurality of operating stations about the path of said mandrels, means for rotating said mandrels, means at one station for turning inwardly the bottom flange of a cup body on a mandrel including a rotating compound die having an outer ring with an inwardly beveled front edge for encircling and bending said flange inwardly, a plug within said ring for folding said cup flange outwardly, means for moving said die onto said cup flange, means for yieldingly limiting the movement of said outer ring while permitting the relative advancement of said plug, means at one station for rolling down the infolded cup flange including a roll mounted for free rotation, means for swinging said roll into and out of the cup bottom, a rotating roll below said cup flange roll for supporting the cup edge during the opera-

tion of rolling down said infolded flange and means for timing the several instrumentalities with each other.

9. In a paper cup machine the combination of a rotary carrier, a plurality of mandrels projecting radially from the axis of rotation of said carrier, a plurality of operating stations about the path of said mandrels, means for rotating intermittently said carrier for presenting said mandrels successively to successive operating stations, means for rotating said mandrels, means at one station for delivering a flanged cup bottom against the end of said mandrel, means for delivering a body blank about said mandrel, a roll above said mandrel for rotary coaction therewith, blank pasting means below said mandrel including a roll for applying paste to a blank on said mandrel, means at another station for applying gum to the inner face of a cup body end projecting from a mandrel, means at another station for turning inwardly the bottom flange of a cup body on a mandrel including a die capable of freely rotating with the cup body while in engagement therewith and means at another station for rolling down the infolded cup flange.

10. In a paper cup machine the combination of a rotary carrier, a plurality of mandrels projecting radially from the axis of rotation of said carrier, a plurality of operating stations about the path of said mandrels, means for rotating intermittently said carrier for presenting said mandrels successively to successive operating stations, means for rotating said mandrels, means at one station for delivering a flanged cup bottom against the end of said mandrel, means for delivering a body blank about said mandrel, a roll above said mandrel for rotary coaction therewith, blank pasting means below said mandrel including a roll for applying paste to a blank on said mandrel, means at another station for applying gum to the inner face of a cup body end projecting from a mandrel comprising a rotating gum applying roll and means for supplying said roll with gum; means at another station for turning inwardly the bottom flange of a cup body on a mandrel including a rotating compound die having an outer ring with an inwardly beveled front edge for encircling and bending said flange inwardly, a plug within said ring for folding said cup flange outwardly and means for moving said die onto said cup flange; means at another station for rolling down the infolded cup flange including a roll mounted for free rotation, means for swinging said roll into and out of the cup bottom and means for timing the several instrumentalities with each other.

11. In a paper cup machine the combination of a rotary carrier, a plurality of mandrels projecting radially from the axis of

rotation of said carrier, a plurality of operating stations about the path of said mandrels, means for rotating intermittently said carrier for presenting said mandrels successively to successive operating stations, means for rotating said mandrel, means at one station for delivering a flanged cup bottom against the end of said mandrel, means for delivering a body blank about said mandrel, a roll above said mandrel for rotary coaction therewith and blank pasting means below said mandrel including a roll for applying paste to a blank on said mandrel; means at another station for applying gum to the inner face of a cup body end projecting from a mandrel, means at another station for turning inwardly the bottom flange of a cup body on a mandrel including means at another station for rolling down the infolded cup flange and means at another station for discharging a bottomed cup from a mandrel including a movable mandrel head and means contiguous to said station for moving said mandrel head from its seat and said cup from the mandrel.

12. In a paper cup machine the combination of a rotary carrier, a plurality of mandrels projecting radially from the axis of rotation of said carrier, means for rotating intermittently said carrier for presenting said mandrels successively to successive operating stations, means for rotating said mandrels, means coacting with said carrier for forming and delivering a flanged cup bottom against the end of a mandrel at one station, means for delivering a body blank to said mandrel and for wrapping and securing said blank about said bottom and mandrel, means at another station for folding in the projecting edge of the cup toward the flange of said bottom, means at another station for rolling the edge of the cup against the flange of said bottom, means at another station for discharging a bottomed cup from a mandrel including a movable mandrel head and means contiguous to said station for moving said mandrel head from its seat and said cup from the mandrel, a second rotary carrier in cooperative relation to said first mentioned carrier, a plurality of conical cup holders projecting radially from the axis of rotation of said second carrier, a plurality of operating stations about the path of said cup holders and means for rotating said cup holders, the first operating station of said second rotary carrier being opposite and in coacting relation to the discharging station of said first carrier whereby when a cup is discharged from a mandrel of said first carrier it is received into a cup holder of said second carrier.

13. In a paper cup machine the combination of means for forming a two piece paper cup comprising a rolled body having a flanged bottom therein, including a rotary carrier, a

plurality of rotating cup carrying mandrels on said carrier, means for rotating intermittently said carrier, a discharging station for said carrier, means for discharging a cup from a mandrel at the discharging station, a second rotary carrier in cooperative relation to said first mentioned carrier, a plurality of cup holders projecting radially from the axis of rotation of said second carrier, a plurality of operating stations about the path of said cup holders, means for rotating intermittently said carrier in coacting time with said first carrier, means for rotating said cup holders, the first operating station of said second rotary carrier being opposite and in coacting relation to the discharging station of said first carrier whereby when a cup is discharged from a mandrel of said first carrier it is received into a cup holder of said second carrier, means at one station for applying gum to the inner face of a cup body mouth in a cup holder and means for timing the several instrumentalities with each other.

14. In a paper cup machine the combination of means for forming a two piece paper cup having a rolled body and a flanged bottom therein, including a rotary carrier, a second rotary carrier in cooperative relation to said first mentioned carrier, a plurality of cup holders projecting radially from the axis of rotation of said second carrier, a plurality of operating stations about the path of said cup holders, means for rotating intermittently said carrier in coacting time with said first carrier, means for rotating said cup holders, means for delivering at one station, said cup, mouth out, into one of said cup holders, means at another station for applying gum to the inner face of a cup body mouth in a cup holder comprising a rotating gum applying roll, means for swinging said roll into and out of engaging relation with the cup body, means for supplying said roll with gum and means for timing the several instrumentalities with each other.

15. In a paper cup machine the combination of means for forming a two piece paper cup having a rolled body and a flanged bottom therein including a rotary carrier, a second rotary carrier in cooperative relation to said first mentioned carrier, a plurality of conical cup holders projecting radially from the axis of rotation of said second carrier, a plurality of operating stations about the path of said cup holders, means for rotating intermittently said carrier in coacting time with said first carrier, means for rotating said cup holders, means for delivering at one station, said cup, mouth out, into one of said cup holders, a rotating compound die having an outer ring with an inwardly beveled front edge for encircling and bending said cup mouth inwardly, a plug within said ring for folding said cup mouth against the inside of the cup, means for moving said die onto

said cup mouth, means for yieldingly limiting the movement of said outer ring while permitting the relative advancement of said plug and means for timing the several instrumentalities with each other.

16. In a paper cup machine the combination of means for forming a two piece paper cup having a rolled body and a flanged bottom therein including a rotary carrier, a second rotary carrier in cooperative relation to said first mentioned carrier, a plurality of cup holders projecting radially from the axis of rotation of said second carrier, a plurality of operating stations about the path of said cup holders, means for rotating intermittently said carrier in coacting time with said first carrier, means for rotating said cup holders, means for delivering at one station, said cup, mouth flange out, into one of said cup holders, means at another station for applying gum to the inner face of a cup body mouth in a cup holder, means at another station for turning inwardly the flange of the cup mouth including a rotating compound die having an outer ring with an inwardly beveled front edge for encircling and bending said flange inwardly, a plug within said ring for folding said cup flange outwardly, means for moving said die onto said cup flange, means for yieldingly limiting the movement of said outer ring while permitting the relative advancement of said plug and means for timing the several instrumentalities with each other.

17. In a paper cup machine the combination of means for forming a two piece paper cup having a rolled body and a flanged bottom therein including a rotary carrier, a second rotary carrier in cooperative relation to said first mentioned carrier, a plurality of cup holders projecting radially from the axis of rotation of said second carrier, a plurality of operating stations about the path of said cup holders, means for rotating intermittently said carrier in coacting time with said first carrier, means for rotating said cup holders, means for delivering at one station, said cup, mouth flange out, into one of said cup holders, means at another station for applying gum to the inner face of a cup body mouth in a cup holder comprising a rotating gum applying roll, means for swinging said roll into and out of engaging relation with the cup body, means for supplying said roll with gum, means at another station for turning inwardly the flange of the cup mouth including a rotating compound die having an outer ring with an inwardly beveled front edge for encircling and bending said flange inwardly, a plug within said ring for folding said cup flange outwardly, means for moving said die onto said cup flange means for yieldingly limiting the movement of said outer ring while permitting the relative advancement of said plug, means at another

station for rolling down the infolded flange of the cup mouth and means for timing the several instrumentalities with each other.

18. In a paper cup machine the combination of means for forming a two piece paper cup having a rolled body and a flanged bottom therein including a rotary carrier, a second rotary carrier in cooperative relation to said first mentioned carrier, a plurality of cup holders projecting radially from the axis of rotation of said second carrier, a plurality of operating stations about the path of said cup holders, means for rotating intermittently said carrier in coacting time with said first carrier means for rotating said cup holders, means for delivering at one station, said cup, mouth flange out, into one of said cup holders, means at another station for applying gum to the inner face of a cup body mouth in a cup holder, means at another station for turning inwardly the flange of the cup mouth, means at another station for rolling down the infolded cup flange including a roll mounted for free rotation, means for swinging said roll into and out of the cup bottom and means for timing the several instrumentalities with each other.

19. In a paper cup machine the combination of means for forming a two piece paper cup having a rolled body and a flanged bottom therein including a rotary carrier, a second rotary carrier in cooperative relation to said first mentioned carrier, a plurality of cup holders projecting radially from the axis of rotation of said second carrier, a plurality of operating stations about the path of said cup holders, means for rotating intermittently said carrier in coating time with said first carrier, means for rotating said cup holders, means for delivering at one station, said cup, mouth out, into one of said cup holders, means at another station for discharging a cup from a holder and means for timing the several instrumentalities with each other. 95 10 10

20. In a paper cup machine the combination of means for forming a two piece paper cup having a rolled body and a flanged bottom therein including a rotary carrier, a second rotary carrier in cooperative relation to said first mentioned carrier, a plurality of cup holders projecting radially from the axis of rotation of said second carrier, a plurality of operating stations about the path of said cup holders, means for rotating intermittently said carrier in coacting time with said first carrier, means for rotating said cup holders, means for delivering at one station, said cup, mouth flange out, into one of said cup holders, means at another station for discharging a cup from a holder including a duplex plunger slidably axially into each cup holder said plunger having opposite relatively small head segments adapted for engaging the cup bottom and opposite relatively large head segments adapted for engaging

the cup body bottom edge, means for advancing said small head segments at one station to eject a bottomed cup from the holder and means for timing the several instrumentalities with each other.

21. In a paper cup machine the combination of means for forming a two piece paper cup having a rolled body and a flanged bottom therein including a rotary carrier, a second rotary carrier in cooperative relation to said first mentioned carrier, a plurality of cup holders projecting radially from the axis of rotation of said second carrier, a plurality of operating stations about the path of said cup holders, means for rotating intermittently said carrier in coacting time with said first carrier, means for rotating said cup holders, means for delivering at one station, said cup, mouth flange out, into one of said cup holders, means at another station for discharging a cup from a holder including a duplex plunger slidably mounted axially into each cup holder, said plunger having opposite relatively small head segments adapted for engaging the cup bottom and opposite relatively large head segments adapted for engaging the cup body bottom edge, means for advancing said small head segments at one station to eject a bottomed cup from the holder including a lever and a slide actuated by said lever and means for timing the several instrumentalities with each other.

22. In a paper cup machine the combination of means for forming a two piece paper cup having a rolled body and a flanged bottom therein including a rotary carrier, a second rotary carrier in cooperative relation to said first mentioned carrier, a plurality of cup holders projecting radially from the axis of rotation of said second carrier, a plurality of operating stations about the path of said cup holders, means for rotating intermittently said carrier in coacting time with said first carrier, means for rotating said cup holders, means for delivering at one station, said cup, mouth flange out, into one of said cup holders, means at another station for discharging a cup from a holder including a duplex plunger slidably axially into each cup holder, said plunger having opposite relatively small head segments adapted for engaging the cup bottom and opposite relatively large head segments adapted for engaging the cup body bottom edge, means for advancing said small head segments at one station to eject a bottomed cup from the holder, means for advancing said large head segments at another station to eject a bottomless cup from the holder and means for timing the several instrumentalities with each other.

23. In a paper cup machine the combination of means for forming a two piece paper cup having a rolled body and a flanged bottom therein including a rotary carrier, a second rotary carrier in cooperative relation to

said first mentioned carrier, a plurality of cup holders projecting radially from the axis of rotation of said second carrier, a plurality of operating stations about the path of said cup holders, means for rotating intermittently said carrier in coacting time with said first carrier, means for rotating said cup holders, means for delivering at one station, said cup, mouth flange out, into one of said cup holders, means at another station for turning inwardly the flange of the cup mouth, means at another station for rolling down the infolded cup flange including a roll mounted for free rotation, means for swinging said roll into and out of the cup bottom, means at another station for discharging a cup from a holder including a duplex plunger slidably mounted axially into each cup holder, said plunger having opposite relatively small head segments adapted for engaging the cup bottom and opposite relatively large head segments adapted for engaging the cup body bottom edge, means for advancing said small head segments at one station to eject a bottomed cup from the holder and means for timing the several instrumentalities with each other.

24. In a paper cup machine the combination of means for forming a two piece paper cup having a rolled body and a flanged bottom therein including a rotary carrier, a second rotary carrier in cooperative relation to said first mentioned carrier, a plurality of cup holders projecting radially from the axis of rotation of said second carrier, a plurality of operating stations about the path of said cup holders, means for rotating intermittently said carrier in coacting time with said first carrier, means for rotating said cup holders, means for delivering at one station, said cup, mouth flange out, into one of said cup holders, means at another station for applying gum to the inner face of a cup body end projecting from a holder, means at another station for turning inwardly the flange of the cup mouth, means at another station for rolling down the infolded cup flange, means at another station for discharging a cup from a holder including a duplex plunger slidably axially into each cup holder, said plunger having opposite relatively small head segments adapted for engaging the cup bottom and opposite relatively large head segments adapted for engaging the cup body bottom edge, means for advancing said small head segments at one station to eject a bottomed cup from the holder and means for timing the several instrumentalities with each other.

25. In a paper cup machine the combination of means for forming a two piece paper cup having a rolled body and a flanged bottom therein including a rotary carrier, a second rotary carrier in cooperative relation to said first mentioned carrier, a plurality of

- cup holders projecting radially from the axis of rotation of said second carrier, a plurality of operating stations about the path of said cup holders, means for rotating intermittently said carrier in coacting time with said first carrier, means for rotating said cup holders, means for delivering at one station, said cup, mouth flange out, into one of said cup holders, means at another station for applying gum to the inner face of a cup body end projecting from a holder, means at another station for turning inwardly the flange of the cup mouth, means at another station for rolling down the infolded cup flange, means at another station for discharging a cup from a holder including a duplex plunger slideable axially into each cup holder, said plunger having opposite relatively small head segments adapted for engaging the cup bottom and opposite relatively large head segments adapted for engaging the cup body bottom edge, means for advancing said small head segments at one station to eject a bottomed cup from the holder, means for advancing said large head segments at another station to eject a bottomless cup from the holder and means for timing the several instrumentalities with each other.
26. An organized machine for making two piece paper cups including in combination, means for supporting a stack of body blanks of annular sector shape, means for separating and advancing said blanks one at a time to body forming means, a rotary carrier, a plurality of mandrels projecting radially from the axis of rotation of said carrier, means for rotating intermittently said carrier for presenting said mandrels successively to successive operating stations, means for rotating said mandrels, means for punching a bottom blank from a web of paper, means for turning up a flange on said blank to form a flanged cup bottom, means for delivering a flanged cup bottom against the end of said mandrel, means for delivering a body blank about said mandrel, a roll above said mandrel for rotary coaction therewith, blank pasting means below said mandrel including a roll for applying paste to a blank on said mandrel, means at one station for applying gum to the inner face of a cup body end projecting from a mandrel, means at one station for turning inwardly the bottom flange of a cup body on a mandrel, means at one station for rolling down the infolded cup flange including a roll mounted for free rotation, means for swinging said roll into and out of the cup bottom, means for discharging the cup from the mandrel and means for timing the several instrumentalities with each other.

In witness whereof, I hereby affix my signature this 15th day of March, 1927.

CHARLES F. SMITH.
